United States Patent

Des. 236,715
Patented Sept. 9, 1975

236,715

PREFOAMED EXPANSION JOINT

William J. Patterson, Burlington, Iowa, assignor to Midwest Manufacturing Corporation, Burlington, Iowa

Filed June 11, 1973, Ser. No. 368,647

Term of patent 14 years

Int. Cl. D25—01

U.S. Cl. D13—6

FIG. 1 is a perspective view of a prefoamed expansion joint showing my new design,

FIG. 2 is a side view thereof, the opposite side being the same,

FIG. 3 is a top view thereof,

FIG. 4 is a bottom view thereof, and

FIG. 5 is an end view thereof, the opposite end being the same.

I claim:

The ornamental design for a prefoamed expansion joint, as shown and described.
